CONDUIT CLOSURE CAP

William G. Rowell, Quincy, Mass., assignor to Scully Signal Company, Melrose, Mass., a corporation of Massachusetts

Filed Mar. 4, 1959, Ser. No. 54,840

Term of patent 14 years

(Cl. D91—1)

Fig. 1 is a top plan view of the conduit closure cap showing my new design.

Fig. 2 is a side elevation of Fig. 1.

Fig. 3 is a bottom plan view of Fig. 1.

Fig. 4 is a sectional view taken on the line 4—4 of Fig. 1.

I claim:

The ornamental design for a conduit closure cap, as shown.
